UNITED STATES PATENT OFFICE.

WILLIAM A. HARVEY, OF SCRANTON, PENNSYLVANIA.

BRANCH CONNECTOR FOR ELECTRIC CONDUCTORS.

1,358,731.

Specification of Letters Patent. Patented Nov. 16, 1920.

Application filed February 25, 1918. Serial No. 219,105.

To all whom it may concern:

Be it known that I, WILLIAM A. HARVEY, a citizen of the United States, and resident of Scranton, in the county of Lackawanna, 5 and State of Pennsylvania, have invented certain new and useful Improvements in Branch Connectors for Electric Conductors, of which the following is a specification.

The present invention relates in general 10 to connectors for electric conductors and more particularly to a branch connector for electric conductors.

In lighting systems it is often desirable 15 to provide a droplight in some particular part of the room and as now practised the means for tapping the light from the supply circuit is generally accomplished by a spliced joint which is soldered and wrapped with insulating tape to meet the requirements 20 of the underwriters. Joints of this kind besides being more or less difficult to make never present a neat appearance. There are also other features which make it undesirable to employ the present methods 25 in connecting the droplight, and the present invention has for its object to overcome these conditions by providing a connector which will not only produce satisfactory 30 results from a mechanical standpoint but which will also present a neat and pleasing appearance.

A further object of the invention is to 35 provide means whereby the connector may be supported from the wall or ceiling along which the conductor extends, and to so construct this wall or ceiling supporting means that it may be done away with if its use is 40 not required.

Further objects will appear upon reference 45 to the accompanying drawing and the following detail description.

In said drawing:

Figure 1, is a side view of a conductor 50 illustrating the application of the invention;

Fig. 2, is a side view of the connector with the cover removed;

Fig. 3, is a sectional view of the connector;

55 Fig. 4, is a sectional view of the conductor on the line 4-4 of Fig. 3;

Fig. 5, is a cross section of the connector on the line 5-5 of Fig. 4;

Fig. 6 is a cross section on the line 6-6 60 of Fig. 4;

Fig. 7, is a side view of the connector

illustrating the use of the wall or ceiling supporting means; and

Fig. 8, is a detail view of the plate which is employed in supporting the connector 60 from the wall or ceiling.

Referring to the drawings in detail, *a* represents an electric conductor of a conventional type and from which it is desirable to connect a branch or droplight cord such 65 as *b*. In making the connection the conductor *a* will be severed and a portion of the insulation and fabric removed so that the confronting ends of the twin wires *c* and *d* may be manipulated to present the severed 70 ends in a position whereby they may be attached to the connector. The insulation and fabric of the droplight cord or conductor *b* is also removed at its attached end in order that the ends of the wires may be manipulated 75 to be attached to the connector.

The connector in its desired form preferably comprises an oblong shaped insulating block 5, having a top piece 6, with an overhang such as at 7, and a cover 8, which is 80 removably secured to the block 5 by means of the small bolts 9 which are carried by the cover and pass through suitable openings in the block 5 which are made to receive them. The overhang 7 of the top 6 overlies the upper edges of the cover and provides a substantially dust and water proof joint. The block 5 is cut away to provide sufficient room for attaching the ends of the respective wires to the binding posts, and in 85 connecting the wires the loose ends *c* and *d* of the twin wires contained in the conductor *a* are passed through the opening 10 in each end of the block, from which point they are divided and pass through openings 95 11 and 12 made to receive them at right angles to the openings 10 and on opposite sides of the axis thereof. After they have 100 been passed through these openings 11 and 12 they are again bent at right-angles to overlie the sides of the block and with their 105 ends attached to suitable binding posts 13 and 14. The binding posts 13 and 14 are mounted on plates 15 provided on opposite sides of the block and with their ends received in openings in the block. The plates 15 are secured to the block by means of the small screws 16 which are embedded in the block in staggered relation to each other so as not to have their confronting ends opposite each other.

One important feature of the present in-

vention resides in the manner by which the ends of the wires *c* and *d* are secured to their respective binding posts. In this instance it is highly desirable that some means other than their attachment to the binding post be relied on to secure them to the connection or the block in order to overcome the possibility of tension on the conductor *a* breaking them loose from the block. This is accomplished, however, by means of presenting the ends of the wires to the binding posts in such a way as to cause a gripping or biting effect to be produced between the ends of the wires and the openings which receive them. The effect produced will be readily appreciated from Fig. 4 of the drawing. As an additional safeguard to prevent the ends of the wires from becoming loose solder may be employed, but if the ends of the wires are properly presented through the openings in the block as proposed by the present invention it will not be necessary to use solder.

The droplight cord or conductor *b* is attached to the connector in substantially the same manner as the severed ends of the conductor *a*, that is to say, the two ends of the wires *e* and *f* contained in the cord are presented through a vertical opening 17 in the bottom of the block 5 provided intermediate its ends. The bottom of the cover also has an opening registering with the opening 17. This opening 17 does not extend through the block, but terminates below the top thereof. On each side and at right angles to the opening 17 are the openings 18 and 19 made to receive the ends *e* and *f* contained in the cord *b* after they have been passed through the opening 17. After being divided and passed through these openings 18 and 19 the ends are attached to binding posts 20 and 21 mounted on each of the plates 15. The same gripping effect is produced between the wires *e* and *f* and the openings which receive them in this instance as that produced with the ends *c* and *d* of

the wires contained in the conductor *a*. In practice the block 5 and its cover may be made of any suitable insulating material either molded or otherwise produced. 50

Referring to Fig. 7 and the wall or ceiling attaching means, it is very often necessary to support the conductor *a* especially if any number of branch connections are to be used on the same line. When this is necessary a plate 22 is provided of substantially the same dimensions as the top of the connector and is provided with two openings 23, made to receive the ends of the small bolts 9. A suitable wood screw 24 or the like is employed to attach the connector to the wall or ceiling. The head of the screw is seated in the countersunk opening 25 and enables the head of the screw to lie flush with the surface of the plate 22. 55 60 65

I claim:

1. In a branch connector for electric conductors, an insulating block having openings in its opposite ends, chambers in said block lying parallel to and spaced from 70 said openings, a passage-way connecting said openings and said chambers and lying at right angles to said openings, a circuit completing means mounted on said block, and means carried by the last-named means 75 for attaching thereto the individual wires of a conductor.

2. In a branch connector, an insulating block having openings therein at its opposite ends and an opening therein intermediate its ends and lying at right angles to the first-named openings, chambers in said block lying parallel to and spaced from said openings, passage-ways connecting said chambers and said openings and lying at 85 right angles to said openings, circuit completing means carried by said block, and means for attaching thereto individual wires of a conductor. 80

The foregoing specification signed this 90 4th day of February, 1918.

WILLIAM A. HARVEY.
